UNITED STATES PATENT OFFICE.

ODDIE HORNER, OF GREENVILLE, OHIO.

REFRIGERATING MECHANISM.

Application filed January 13, 1922. Serial No. 529,049.

To all whom it may concern:

Be it known that I, ODDIE HORNER, a citizen of the United States, residing at Greenville, in the county of Darke and State of 5 Ohio, have invented certain new and useful Improvements in a Refrigerating Mechanism, of which the following is a specification.

The present invention relates to a refrigerating mechanism and has for its principal 10 object to provide new and improved, as well as economical means of freezing ice, or producing cold with a mechanically operated refrigerating machine.

Another object is to provide novel means 15 of freezing ice with the apparatus including a combination expansion box and ice tray compartment.

Another object of the invention is to combine 20 the expansion box with an expansion coil.

Another object is to provide means of regulating the refrigerant from the supply 25 line to the combination expansion box and ice tray compartment by means of a vacuum controlled valve mounted on a base or platform entirely exposed to view enabling one 30 to operate the valve completely, it being free from the usual valve housing or boxes which usually make such valves inaccessible 35 for either the regulation or attention they may require from time to time.

It is the intention of the invention to improve generally, and to enhance the utility 40 of devices of this type to which the present invention appertains.

With the above and numerous other objects in view, which will appear as the description proceeds, the invention resides in 45 the combination and arrangement of parts, and in the details of construction hereinafter described and claimed; it being understood that changes in the precise embodiment of the invention herein disclosed, can be made within the scope of what is claimed without departing from the spirit of the invention.

In the drawing:—

Figure 1 is a rear elevation of the device embodying my invention.

Figure 2 is a side elevation thereof,

Figure 3 is a fragmentary detail view of the manifold used in connection with the coil.

Figure 4 is a longitudinal section taken 55 on the line 4—4 of Figure 3 looking in the direction of the arrow,

Figure 5 is an enlarged detailed fragmentary view of the bottom end of the thermostat coil.

Figure 6 is a vertical section taken 60 through the vacuum controlled valve.

Figure 7 is a section taken on the line 7—7 of Figure 6 looking in the direction of the arrow, and

Figure 8 is a side elevation of the combined expansion and ice tray box, a portion 65 thereof being shown in section.

Referring to the drawing in detail it will be seen that assembled views have been shown in Figures 1 and 2 wherein the combined expansion box and ice tray compartment is shown at the bottom of the apparatus and is fed with the refrigerant by the pipe 17 leading from the vacuum controlled valve 6. The refrigerant is introduced into 70 the coils through the pressure or supply line 15. A vacuum being pumped into the coil assembly produces a contraction on the diaphragm 5 and in this manner operates the vacuum controlled valve, opening the 75 same by means of a lever 6' which is connected to the yoke 18 mounted on the needle valve stem 10. This lever is pivoted on the rod 8 extending from the cap of the valve 6 producing a fulcrum therefor. When this 80 valve is opened by the vacuum, the refrigerant, which is in the form of liquid, passes through the small opening of the vacuum controlled valve into the expansion box 17 and thence into the expansion box 2 and is 85 here further expanded into gas. The construction of the expansion box is shown to advantage in Figure 8 and is provided with an ice tray compartment 2^A carried interiorly 90 thereof and spaced therefrom so that as the refrigerant expands it will absorb heat in the compartment 2^A and the ice formed therein will be very dry since the temperature therein would probably be approximately ten to twelve degrees above zero 95 (Fahrenheit). The expansion coil system 1 is in communication with the expansion box 2 as is shown also in Figure 8 so that the refrigerant may continue its expansion 100 therein and from experience I have found that the temperature of a compartment containing the coils would be approximately forty degrees above zero (Fahrenheit). When the machine, that is the compressor, (not shown) stops operating, the weight 7 110 causes the lever 6' to close the valve.

As the gas rises in the expansion coil sys-

tem its cold is diminished by the heat it has absorbed and it is returned to the compressor and there recompressed and condensed into liquid in a manner well understood in the art thereby completing one full cycle, it being ready again to go through the processes above mentioned.

The vacuum controlled valve 6 has mounted on the needle 10 a corrugated copper diaphragm 11 supported by two brass follow plates 12. The diaphragm 11 being held securely between the valve body flanges 9 and the valve cap 8 to prevent any leak of gas during periods of time when the machine is idle, and to provide easy and free movement of the needle point and also to omit the use of packing of any kind around the needle point. When the machine is not in operation the liquid which has not been fully expanded into gas continues to expand, thereby producing cold for some time after the machine has stopped, this also creating a pressure in the expansion coil which in turn expands the sylphon or diaphragm 5 which is in communication therewith through the pipe 16 thereby raising lever 6 at the top of the diaphragm 5 thus closing down the needle valve securely. This method enables the valve to function properly and does not require a bundlesome heavy weight. The pipe 18 leads to a compression.

The thermostat coil 1^A is embodied in the expansion coil in such a manner as to make the whole a compact assembly producing uniformity of design which will be an advantage in the rapid and economical production of these machines; also lessen the need of experienced men to install and charge the thermostat.

The purpose of the thermostat coil is clearly understood by referring to Figures 1, 2, 3, 4 and 5. The lower end of the thermostat coil is sealed or closed in any desired manner as at 22 and its upper end is connected to the manifold 3 in a blind hole 30 communicating with the indenture 31 in which is situated the valve seat 32. The needle valve 19 is threadedly mounted so as to engage and disengage with the valve seat 32 and suitable packing 23 is provided therefor. The head 23' of the needle valve 19 is formed so as to be fitted with a tool when it is desired to manipulate the valve. A cap 20 protects the same from being tampered with accidentally or by unauthorized persons. On the thermostat coil is located a boss suitably secured to which is attached a tube 21 which leads to an automatic diaphragm controlling device (not shown) such as are now commonly in use.

To charge the thermostat coil 1^A after the refrigerating coil has been charged with the refrigerant and the machine allowed to re-

main idle for a period of time, the pressure in the expansion coil equalizes with that contained in the machine proper (not shown). Then by removing the valve cap 20 by means of a socket wrench or any other suitable implement the square end of the needle valve is engaged and actuated for opening the same and allowing the refrigerant to flow from the expansion coil 1 into the thermostat coil 1^A situated at the front of the expansion coil preferably and being the first coil in the same. The needle valve 19 is then closed and the valve cap 20 replaced thereby sealing the thermostat coil and preventing accidental or otherwise interference therewith. To set the thermostat the machine is started allowing it to operate until the temperature in the coil compartment reaches the desired temperature and then by adjusting the regulating spring on controls (not shown) until the control switch cuts out, and an automatic thermostatic control is the result. The pressure within the thermostat coil 1^A will always be approximately the same as the pressure within the expansion coil 1. The pressure of this thermostat coil will therefore allow of expansion and contraction of the sylphon or diaphragm of the automatic diaphragm in accordance with the temperature in and about the expansion coil so that the controlling device in turn will operate the switch in the circuit of the electric motive power for operation of the compressor.

Having thus described my invention what I claim as new is:

1. In combination, a coil including a plurality of sections, an expansion box communicating with some of said coil sections, a manifold in communication with said sections, and a valve disposed between the section which is not in communication with the expansion box and the manifold in the manner and for the purpose specified. 100

2. In combination, a coil including a plurality of sections, an expansion box communicating with the sections of said coil, a manifold in communication with said sections, a thermostatic pipe having one end closed and its other end communicating with said manifold, and a valve disposed between the thermostatic pipe and the manifold. 105

3. In combination, a coil including a plurality of sections, an expansion box communicating with the sections of said coil, a manifold in communication with said sections, a thermostatic pipe similar in appearance to the sections of said coil having its lower end mounted on said expansion box but not in communication therewith and its upper end communicating with said manifold, and a valve disposed between the thermostatic pipe and the manifold. 120

In testimony whereof I affix my signature.
ODDIE HORN.
